UNITED STATES PATENT OFFICE.

ARTHUR M. GODWIN, OF GRAND RAPIDS, MICHIGAN, ASSIGNOR TO WOLVERINE BUMPER & SPECIALTY COMPANY, OF GRAND RAPIDS, MICHIGAN, A CORPORATION OF MICHIGAN.

DESIGN FOR A CLAMP FOR VEHICLE BUMPERS.

Application filed June 19, 1924. Serial No. 9,902. Term of patent 3½ years.

To all whom it may concern:

Be it known that I, ARTHUR M. GODWIN, a citizen of the United States, residing at No. 636 Fountain Street NE, Grand Rapids, in the county of Kent and State of Michigan, have invented a new, original, and ornamental Design for a Clamp for Vehicle Bumpers, of which the following is a specification, reference being had to the accompanying drawings, forming a part thereof, in which—

Figure 1 is a front or face view of a clamp for vehicle bumpers showing my design;

Figure 2 is a longitudinal sectional view thereof taken on line 2—2 of Figure 1;

Figure 3 is a transverse sectional view thereof taken on line 3—3 of Figure 1; and

Figure 4 is another transverse sectional view thereof taken on line 4—4 of Figure 1.

I claim:

The ornamental design for a clamp for vehicle bumpers substantially as shown.

ARTHUR M. GODWIN.
